UNITED STATES PATENT OFFICE

CHARLOTTE A. McGEE, OF JACKSON, MICHIGAN, ASSIGNOR TO THE CORONET CORSET COMPANY, OF SAME PLACE.

CORSET.

SPECIFICATION forming part of Letters Patent No. 323,706, dated August 4, 1885.

Application filed April 18, 1882. (No model.)

To all whom it may concern:

Be it known that I, CHARLOTTE A. McGEE, a citizen of the United States, residing at Jackson, in the county of Jackson and State of Michigan, have invented certain new and useful Improvements in Corsets, of which the following is a specification, reference being had therein to the accompanying drawings.

Figure 1 is a side elevation of a portion of a corset having my invention applied thereto. Fig. 2 is a horizontal section taken on the line *x x*, Fig. 1.

The invention relates to certain novel features, which will be hereinafter specifically pointed out and claimed.

In the drawings, A represents one of the front sections, in the lower part of which may be formed an opening or slit provided with the usual lacing. The corset-front is provided with a number of bones or steels, A', which are inserted in pockets in the usual manner, the pockets being formed between the two layers of material by lines of stitching. At the front edge of section A is a busk, D, provided with loops *d*, adapted to engage with hooks, studs, or buttons upon the corresponding busk at the front edge of the opposite section.

a is a supplemental bone-pocket formed of a piece of fabric separate and apart from the fabric of which the section A is made, and secured by a line of stitching at one edge of the pocket to the rear edge of the front section, along a line adjacent to the side section, and also adjacent to the stiffening-strips A'. The pocket is closed at its lower end, preferably by means of the binding C; but it need not be included at its lower end within said binding. The pocket is open at its upper end for the reception of the bone or steel, as shown in Fig. 1 at *a'*, one thickness of fabric being broken away to show the upper end of the steel; and it will be readily understood that such construction facilitates the removal of the bone or steel for the purpose of reversing its position relative to the body of the corset, or for the purpose of replacing it with either a stiffer or a more flexible bone or steel; or two or more bones or steels may be inserted in said pocket, as circumstances or the desired stiffness may indicate.

The bone or steel may be withdrawn from the pocket at any time if the wearer so desires, as it is in the nature of a supplemental stay, whereby the stiffness of the corset can be regulated at the option of the wearer.

I am aware that it is old to provide a corset along its front edges with open-end pockets adapted to receive supplemental busks, and also that flaps, either with or without stiffening devices, have been employed at the same places on a corset in order to protect the wearer from the clasping-busks.

E E F is the side piece of the corset. The portions E E are cut on the bias of the cloth, as indicated in the drawings, the intermediate portion, F, being cut straight with the grain of the cloth and provided with two or more pockets, in which are inserted cords *e e*.

The pieces E E may be cut of any desired width at their lower ends, relative to their widths near their centers or upper ends, in order to produce the desired flare at the lower part of the corset; and it will be readily understood that by reason of these parts E E being cut on the bias of the cloth the corset will much more readily conform to and assume the desired shape than if these pieces were cut with the grain of the cloth, while the employment, in combination therewith, of the central piece, F, which is corded, will impart sufficient stiffness to prevent undewrinkling, and therefore make it comfortable for the wearer. It will be seen that the surfaces of the bias pieces E E are uninterrupted from edge to edge—that is, not crossed in any direction either by stitching or stiffening devices, which, as will be understood, would prevent the usefulness of the pieces E; and when I employ the term "uninterrupted surfaces" in connection with these bias pieces I mean that they are not crossed either with stitches, stiffeners, or otherwise, so as to prevent the stretching or elastic action of the cloth.

I am aware that side pieces of corsets have been cut on the bias and of such length as to overlap the hip of the wearer, and that such bias pieces have been found desirable so far as regards their flexibility and elasticity. But I have discovered that in practice, when such side pieces have been made of much greater length than those shown in my Patent No. 194,045, they are subject to transverse wrin-

kles; hence the necessity for adopting some means for preventing such wrinkling; and I have found that by making each side piece of three members—that is to say, a central member cut with the grain and two adjacent members cut bias—and then cording the central member, I can overcome this defect without materially interfering with the desired flexibility and elasticity.

10 What I claim is—

1. In a corset, the combination, with the back section and the side section, of a front section, A, provided near its rear edge adjacent to the side section with a stiffening strip or strips, A', and a supplemental open pocket secured to the rear edge of the front section along a line adjacent to the side section and to the stiffeners A', and adapted to receive a stiffening-strip which can be removed and re-
20 placed at will, substantially as set forth.

2. In a corset, in combination with the front section and the back section, the hip portion consisting of the pieces E E cut on the bias of the cloth and having uninterrupted surfaces from edge to edge, and the piece F between 25 the two pieces E, cut with the thread of the cloth and provided with stiffening devices, whereby the hip-section is rendered elastic by reason of the pieces E cut on the bias, and is prevented from wrinkling by the stiffened 30 piece F, substantially as set forth.

In testimony whereof I have affixed my signature in presence of two witnesses.

CHARLOTTE A. McGEE.
